UNITED STATES PATENT OFFICE.

DANIEL ANTON ZURBRIGG, OF MILFORD, DELAWARE, ASSIGNOR TO THE L. D. CAULK COMPANY, OF MILFORD, DELAWARE, A CORPORATION OF DELAWARE.

DESIGN FOR A DENTAL PLASTIC INSTRUMENT.

53,955.

Specification for Design.

Patented Oct. 7, 1919.

Application filed May 20, 1918. Serial No. 235,734. Term of patent 14 years.

To all whom it may concern:

Be it known that I, DANIEL ANTON ZURBRIGG, a subject of the King of Great Britain, residing at Milford, in the county of Sussex, State of Delaware, have invented a new, original, and ornamental Design for a Dental Plastic Instrument, of which the following is a specification, reference being had to the accompanying drawing, forming part thereof.

The figure is a perspective view of a dental plastic instrument embodying my new design.

I claim:

The ornamental design for a dental plastic instrument, as shown.

DANIEL ANTON ZURBRIGG.

Witnesses:

W. G. SAMMONS,
WM. S. DAUGHERTY.
